A. G. HUPFEL,
FEED CONNECTION FOR HOP STRAINERS AND THE LIKE.
APPLICATION FILED MAR. 24, 1917.

UNITED STATES PATENT OFFICE.

ADOLPH G. HUPFEL, OF NEW YORK, N. Y.

FEED CONNECTION FOR HOP-STRAINERS AND THE LIKE.

1,296,187.

Specification of Letters Patent.

Patented Mar. 4, 1919.

Application filed March 24, 1917. Serial No. 157,231.

To all whom it may concern:

Be it known that I, ADOLPH G. HUPFEL, a citizen of the United States, and a resident of New York, county of New York, and State of New York, have invented a new and useful Improvement in Feed Connections for Hop-Strainers and the like, of which the following is a specification, the principle of the invention being herein explained and the best mode in which I have contemplated applying that principle, so as to distinguish it from other inventions.

The present invention relates to a feeding mechanism for supplying the material to be treated to a hop strainer or like mechanism of the general construction illustrated in the United States Letters Patent No. 1,092,994 issued to me April 14, 1914, and comprising a receptacle in which the material is strained and pressed.

The receptacle is rotatably mounted and the present invention relates to feeding mechanism which can be quickly attached to the rotatable receptacle for feeding the material, and which may then be easily removed before the receptacle will be rotated. Convenient means for closing the openings are also provided, the whole forming a very compact feeding device and one which can be readily attached to the strainer. To the accomplishment of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Figure 1 is a sectional view of part of the strainer with my feeding mechanism attached. Fig. 2 is a section showing the feeding mechanism removed and the closure plugs in place; and Fig. 3 is a front elevation showing the locking mechanism for one of the plugs.

The present feeding mechanism is adapted to be used with a rotatable strainer (only partly shown), the rotatable receptacle 1 having an operating screw 2 which is held in a removable head or manhole cover 3 by a lock 4. An inner pressure head 5 is also provided. This mechanism is only partly shown as it merely represents one of many forms

with which my feeding mechanism may be used.

The feeding mechanism consists of an elbow or sleeve 6 which will be so mounted as to swing, the swing mounting consisting of a flanged pipe 50, the flange being curved as at 51 and adapted to be received within the upper flanged end 7 of the elbow. Bayonet lugs 52 are mounted in the end 7 and pass through slots 53 in the pipe 50 to allow the elbow to be swung clear of the cover 3. The lugs are loosely mounted in the slots and with the curved flange permit sufficient pivotal movement to allow the pipe to be withdrawn and swung clear. Other forms of mounting may be employed depending upon the conditions to be met.

In the cover 3 and the pressure head 5 are aligned openings 8 and 9 which are connected by sleeves 10 and 11. The sleeve 10 is rigidly attached to the head 5 by means of bolts 12, and this sleeve is provided with an inner locking ring 25 having openings 26 therein, the purpose of this locking ring being explained later. A second sleeve 11 is mounted within a rim 14 fastened to the cover 3 by the bolts 28. This sleeve 11 is smaller than the inner sleeve 10 and fits into the latter making a leak-proof joint therewith. The sleeve 11 is provided at its outer edge with a raised flange 13 which is adapted to seat against the outer edge 15 of the rim 14. In the face of the flange 13 an annular groove 16 is cut in which a ring 17 formed on the flanged end 18 of the elbow is adapted to fit.

For holding the elbow in place a coupling nut 19 is provided which fits over the elbow, and has a flange 20 adapted to contact with the rear edge of the flange 18 on the elbow. The coupling nut is internally threaded and is adapted to make threaded connection with the screw threads 21 on the rim 14, thus holding the elbow and the sleeve together, the groove and ring affording a leak-proof joint at this point.

When it is desired to operate the receptacle, the coupling nut is unscrewed and the elbow swung back out of the way. The sleeve 11 will then be removed, a cross bar 30 serving as a handle. The inner plug 31 for the pressure head will then be inserted, this plug being formed with radial lugs being adapted to pass through the openings 26 in the ring 25, after which by rotating the plug it will be locked, a slight wedging action being afforded by beveling the lugs. It

has been found possible to make this plug water tight, a rubber washer or gasket being employed if necessary. This plug has a cross bar 32 which serves as a handle.

5 An outer plug 33 is provided for the cover and this plug will have a merely ground fit with the rim 14, but will be of considerable depth. As there is practically no pressure on this plug, a ground fit is sufficient to hold 10 the same in place. A cross bolt 39 is used as a handle.

The operation and use of the device is clear, as the elbow is used simply to feed the work and hops into the strainer and as soon 15 as the latter is filled, the elbow will be removed and the plugs will be put in place to close the apertures. This furnishes a very convenient construction and is very satisfactory as it does away with the leakage always 20 attendant where a continuous feed is used, as then a gland or joint has to be made and the wear after rotating the receptacle makes it hard to prevent leaks.

Other modes of applying the principle of 25 my invention may be employed instead of the one explained, change being made as regards the mechanism herein disclosed, provided the means stated by any of the following claims or the equivalent of such stated 30 means be employed.

I therefore particularly point out and distinctly claim as my invention:—

1. In apparatus of the character described, the combination of a rotatably mounted receptacle provided with an opening at one end for receiving the material to be treated, a swinging sleeve adapted to be removably attached to said drum to furnish the material and means for closing such 40 opening upon removal of said sleeve.

2. In apparatus of the character de-

Copies of this patent may be obtained for five cents each, by addressing the "Commissioner of Patents Washington, D. C."

scribed, the combination of a rotatably mounted receptacle provided with an opening at one end for receiving the material to be treated, a pivotally mounted sleeve for 45 carrying the material, said sleeve being of a size to fit such opening in said receptacle; means for detachably connecting said sleeve to said receptacle; and other means for closing such opening upon removal of said 50 sleeve.

3. In apparatus of the character described, the combination of a rotatably mounted receptacle provided with an opening at one end for receiving the material to 55 be treated, a pivotally mounted sleeve for carrying the material, said sleeve being of a size to fit such opening on said receptacle; a union for detachably connecting said sleeve to said receptacle; and a plug adapted 60 to be received in such opening upon removal of said sleeve to close the same.

4. In apparatus of the character described, the combination of a rotatably mounted receptacle adapted to contain the 65 material to be treated and provided at one end with a pressure head and a removable cover, such cover and head having aligned openings therein, a pivotally mounted sleeve adapted to be removably attached to such 70 cover and having connection with the interior of said receptacle through the opening in such pressure head, means for maintaining said sleeve in position, and other means for closing the opening in such pressure head upon removal of said sleeve.

Signed by me, this 3rd day of February, 1916.

ADOLPH G. HUPFEL.
